FACE GUARD FOR A HELMET

Fred R. Dunning, 3800 Oakes Road,
Brecksville, Ohio 44141

Filed Jan. 3, 1972, Ser. No. 215,261

Term of patent 14 years

Int. Cl. D2—03

U.S. Cl. D2—233

FIG. 1 is a front elevational view of a face guard for a helmet showing my new design;

FIG. 2 is a rear elevational view thereof;

FIG. 3 is a side elevational view, the broken lines showing the outline of a football helmet used for illustration only;

FIG. 4 is a top plan view; and

FIG. 5 is a bottom view.

I claim:

The ornamental design for a face guard for a helmet, as shown and described.
